UNITED STATES PATENT OFFICE.

ADOLPH PETZOLD, OF PHILADELPHIA, PENNSYLVANIA, ASSIGNOR TO JOHN H. BROMLEY, JOSEPH H. BROMLEY, AND EDWARD BROMLEY.

DESIGN FOR A TABLE-COVER.

SPECIFICATION forming part of Design No. 22,651, dated August 1, 1893.

Application filed June 2, 1893. Serial No. 476,398. Term of patent 3½ years.

To all whom it may concern:

Be it known that I, ADOLPH PETZOLD, a citizen of the United States, residing in the city of Philadelphia, State of Pennsylvania, 5 have invented and produced a certain new and original Design for a Table-Cover, of which the following is a full, clear, and exact description, reference being had to the accompanying drawing, forming a part of this specification.

10 My invention has relation to the surface ornamentation of a table cover and consists of the design therefor shown in the accompanying drawing in which the distinguishing features are, first, a floral border of sufficient

15 depth at the four corners to constitute a substantially circular field center. Within the field center is contained a floral wreath, and

within the inner field center formed by the said wreath, are three dogs couchant upon a bank or elevation overlooking a plate or dish. 20

I claim as my invention—

1. The design for a table cover substantially as shown and set forth.
2. The design for the field center consisting of the floral wreath inclosing the dogs 25 couchant; substantially as shown and set forth.

In testimony whereof I have hereunto affixed my signature this 27th day of May, A. D. 1893.

ADOLPH PETZOLD.
